His Attorney.

UNITED STATES PATENT OFFICE.

ALLAN B. HENDRICKS, JR., OF PITTSFIELD, MASSACHUSETTS, ASSIGNOR TO GENERAL ELECTRIC COMPANY, A CORPORATION OF NEW YORK.

HIGH-VOLTAGE BUSHING.

Application filed January 2, 1919. Serial No. 269,288.

To all whom it may concern:

Be it known that I, ALLAN B. HENDRICKS, Jr., a citizen of the United States, residing at Pittsfield, in the county of Berkshire, State of Massachusetts, have invented certain new and useful Improvements in High-Voltage Bushings, of which the following is a specification.

My invention relates to high voltage bushings or insulators for electrical conductors, and has for its object the provision of an improved insulator which is durable, easily manufactured and which may be made in smaller sizes than known bushings having a similar rating and yet possess desirable electrical characteristics.

Insulators built to withstand high voltages will fail either on account of creepage, arc-over or puncture. It has been customary to provide the surfaces of insulators with deep corrugations in order that there may be sufficient creepage distance to withstand the electrical strains without unduly increasing the length of the insulator.

This arrangement however not infrequently results in an uneven distribution of the electrostatic flux over the surface of the insulator so that corona will appear even when the insulating material of which the insulator is constructed is not strained to anything like the working limits of its breakdown strength. As a consequence, in reckoning with these various factors in the design of an insulator, a compromise results at the expense of the size and most economical use of material employed.

In the practice of my invention I provide a principal creepage path with interposed barriers in a dielectric medium other than air and in addition I so control the electrostatic flux distribution that corona does not appear disproportionately to the puncturing qualities of the materials employed, thereby enabling me to make a better disposition of the insulating material than was heretofore known in the art.

For a more complete understanding of the nature and objects of my invention reference should be had to the following description when taken in connection with the accompanying drawing, in which:

Fig. 1 shows an insulator partially in section and partially in elevation which embodies my invention; while Fig. 2 similarly

shows a modified form of insulator embodying my invention.

Referring now to Fig. 1 of the drawing, 10 denotes a conducting tube, which may be the conductor itself to be led through the bushing structure, but is preferably only a housing therefor. This conductor is to be insulated from the surrounding conducting structure or sleeve indicated generally at S. Surrounding the tube 10 is formed an insulating cylinder 11. This cylinder is preferably formed of some homogeneous fibrous insulating material such as shell-lacked paper formed under heat and stops short of the upper end of the tube 10 by some distance as shown at 12 while at the lower end it extends beyond the end of the tube preferably a somewhat greater distance, as shown at 13. The opening at the lower end of cylinder 11 has a conical flare indicated at 14 for a reason presently to be described.

About an intermediate portion of the cylinder 11 is placed a uniform layer 15 of a suitable insulating material, which may conveniently be a wrapping of varnished cambric. This layer has its ends slitted for some distance in an axial direction and folded back to form barriers; the slits being so placed in the superposed layers of the wrapping that they have a staggered relation, while the barriers are with advantage formed by bending the slitted portions sharply back over the ends of sleeve S.

The layer of insulating material 15 is held in place and fitted snugly into the conducting sleeve S, shown as having a ground shield 16 and a flange or collar 17 formed thereon near the upper end.

The collar 17 affords a means for securing the bushing to the cover or wall of the housing enclosing the electrical apparatus served by the bushing for which purpose the collar is provided with bolt openings as shown at 18.

The slitted ends of the insulating layer 15 are formed, at the lower end of sleeve S, into the barrier or collar 19 which is supported in a radial position by the insulating washer 20. This washer 20 is held in place by an insulating distance sleeve 21 which is tightly wedged between this washer and a similar washer 22 supported by insulating dowel pins 24; the latter be-

ing partially embedded for support in the cylinder 11. Since the lower end of the bushing is designed to extend beneath the surface of the oil or other insulating medium in which the electrical apparatus served by the bushing is submerged, all trapped air must be displaced from this end of the bushing structure to insure the proper dielectric strength. To this end the distance sleeve 21 is provided with openings 21' to permit oil to enter and displace air between it and the cylinder 11, also cotton yarn or other insulating material will preferably be inserted at 25 to tightly fill the space between collar 19 and washer 20, thus providing a more nearly homogeneous dielectric medium at this point about the conductor.

The upper end 30 of the insulating layer 20 15 is partially folded back upon itself but it envelops the extended upper end 16 of the conducting sleeve S, which end 16 serves as an electrostatic shield controlling the electrostatic flux passing from the tank to the conductor to get a more desirable distribution, in a well known manner which is set forth in U. S. Letters Patent to Sieber, No. 1,253,736.

The end 30 is held pressed back in a manner similar to collar 19, by means of insulating filling 32 and the superposed insulating distance sleeve 33; the latter being held in place by the pressure exerted by a depending portion 34 of the metallic cap 35. An intervening felt gasket 36 is shown for the purpose of taking up a certain amount of compression and allowing for lost motion of the parts.

The metallic cap 35 rests upon the external insulating cylinder or member 37 which rests on collar 17 and forms the upper portion of the bushing. This member is shown as secured between gaskets 38 and 39 in order to make tight joints both with the cap 35 and the flange 17.

The member 37, when in service, is filled with an insulating compound, preferably petroleum jelly, to a desired height; here indicated at 40. This compound is conveniently introduced through the plug closed opening 41 in cap 35. In order that this compound may readily enter on both sides of the distance sleeve 33, I provide a number of openings 33' near the top and bottom 55 of the sleeve, which openings also permit air to escape and thus avoid air pockets. For a similar reason the openings 34' have been provided in the depending portion 34 of the cap 35.

The exterior contour of the cap 35 is designed to secure a reduction in concentration of the electrostatic flux at the end of the bushing, but obviously the cap may be formed to give any other desired distribution. The portion 34 is also formed to assist

in securing the desired distribution of this flux interiorly of the bushing in a manner set forth in U. S. Letters Patent No. 1,350,925 issued Aug. 24, 1920, on an application by G. Faccioli. The cap 35 has a depressed central cup-shaped portion 42 arranged to snugly fit about the upper end of tube 10 which protrudes from the insulating cylinder 11. This cup-shaped portion 42 contains a compressible helical spring 43 which reacts against the nut or collar 44 which is screwed or otherwise secured upon the protruding tip of the conducting tube 10, which construction provides a convenient means for rigidly retaining the whole bushing structure in assembled relation.

Rotatably mounted upon the nut or collar 44 is the capstan nut 45 which is rigidly secured to the conducting rod 46 (here shown connected by pin 47) which rod 85 passes down inside the tube 10 and serves as the conductor.

The connections to the aerial lead are made on the upper side of the nut 45 as indicated at 48.

The lower end of rod 46 is threaded as shown at 49 for engagement with the upper end of the lead 50 coming from the electrical apparatus not shown which is housed by the casing on which the bushing is mounted.

The end of the lead 50 is submerged beneath the level of the cooling and insulating medium, such as oil, and is surrounded by a wrapping 51 of insulating material having a tapered formation adapted to fit snugly into the flared opening 14 in the cylinder 11. When this lead is drawn up into opening 14 by manipulating the capstan nut 45, the upper end of the lead 50 is drawn snugly into and against the lower end of the conducting tube 10 and a connection is afforded having excellent electrical characteristics enabling the use of an interior bushing structure having smaller proportions for given ratings than anything previously attempted.

In operation, the creepage surface from either end of the conducting tube 10 to the sleeve S, which may be taken as ground potential, is made great. Considering for a moment that from the protruding end shown at 12, the creepage path is over the surface of cylinder 11 down to and over the insulating filling at 32, thence over the end folded back at 30 to the sleeve S. In like manner the creepage path from the end of tube 10 at 13 is made long by means of the washers 20 and 22 on the lower extremity of cylinder 11. The resistances of these creepage paths are designedly so proportioned in length that the bushing will fail in some other manner (preferably by arc over) before it will fail by creepage. The bushing, of course, may fail by creepage over or by appearance of corona on the surface of insulating member 37, but the cap 35 is prefer-

ably so shaped that local concentration of electrostatic flux over the surface of member 37 is avoided thereby obtaining approximately uniform distribution of the stress over the surface of member 37 and substantially maximum efficiency in the utilization of the insulating properties of member 37. The greatest tendency to failure by puncture is across the space between tube 10 and sleeve S. The dielectric strength and thickness of cylinder 11 and of layer 15 are preferably such that failure here is very remote.

The air or dielectric medium exterior to member 37 as a consequence offers the weakest path across which failure may take place. The arcing discharge, in such case, would generally be between the cap 35 and the top of the housing which supports the bushing. It is thus seen that failure by arc-over may take place with my bushing without any permanent injury to the bushing structure.

The relative insulating strengths of the two ends of a bushing made in accordance with my invention are preferably so proportioned that the upper end will fail by arc over before the lower end. The thickness of the insulating material used in the construction is preferably so chosen that a failure by puncture in my bushing will be the last in order to take place, while the flux control which I have provided enables me, by suitably proportioning the parts, to prevent corona from appearing at any point before failure from arc over is about to occur.

When the electrostatic stress components occurring longitudinally over the surfaces of the insulating structure, which can safely be employed over the bushing shown in Fig. 1, must be exceeded, a greater surface to distribute such increased stress components is with advantage provided in the manner illustrated in Fig. 2.

In Fig. 2, 110 denotes the conducting tube which contains the conductor to be insulated. About the tube 110 is formed an insulating cylinder 111; a portion of the tube 110 protruding from the upper end is shown at 112 but stops short of the lower end as shown at 113. The cylinder 111 has a flared lower end 114 to snugly receive the lead from the winding in the same manner as shown in Fig. 1.

Instead of one layer of insulating material being overlaid on the cylinder 111, as in Fig. 1, I here provide a plurality of layers, two being shown, an inner one 115 and an outer one 115' which are surrounded intermediate their ends by the snugly fitting sleeve 116. This sleeve has a flange 117 provided with bolt openings 118.

The ends of the layers 115 and 115' are slotted and folded back in a similar manner to that above described to form collars 119 and 119' respectively at the lower ends, which collars are held back by the distance

sleeves 121 and 121' respectively; intervening washers 120 and 120' being here employed to build up a collar of desired thickness. The distance sleeves 121 and 121' are shown as provided with openings at top and bottom for the same purpose that openings were shown in distance sleeve 21 in Fig. 1.

The distance sleeve 121 bears on a washer 123 held in place by the projecting pins 124 which are secured in the cylinder 111. It is observed that sleeve 121' fits between collars 119 and 119', the latter being turned back against the lower edge of sleeve 116, and is rigidly supported as well as collar 119 thus forming a rigid lower end construction for this form of bushing.

The conducting sleeve 116 in this bushing is also provided with an electrostatic shield 126 over the edge of which is folded back the upper slotted end 130' of the insulating layer 115'. The rounded edge of this end is built up by means of the washer and felt construction shown at 131 to support the distance sleeve 132 interposed between the end 130' and the collar forming end 130 of the insulating layer 115.

Instead of depending on another distance sleeve to be clamped in place by the pressure of the cap on the bushing structure as was done in the first described bushing, I have here illustrated an alternate construction which is simpler and easier to assemble correctly.

The collar 130 is held down by a somewhat elastic washer 133 which is held in place by the insulating cylinder 134. This cylinder 134 is short and is slipped over the upper end of cylinder 111 before the upper bushing structure is put in place and cemented fast to the cylinder 111. This cementing may be readily accomplished by applying shellac to fill the space between the two cylinders and giving the whole a heat treatment.

A metallic cap 135 is slipped about the protruding end of conducting tube 110 to hold the other insulating member 137 in place. This member rests between gaskets 138 and 139 to insure tight joints to keep the insulating compound shown at 140 from leaking out.

The cap 135 is similar to the cap 35 and has a depending flux controlling member 136 and a plug closed opening 141 to admit the insulating compound. It is also provided with a cup-shaped formation 142 containing spring 143 which is compressed by nut or collar 144 which engages with the tip of tube 110 to retain the cap 135 and member 137 in place under pressure. Both the member 136 and sleeve 132 are provided with openings, indicated at 136' and 132' respectively, so that the insulating compound will displace the air which would otherwise be pocketed at these points.

Turning in the nut or collar 144 is the capstan nut 145 having a threaded rod or conductor 146 which is to be rotated into threaded engagement with the lead from the electrical apparatus (not shown) similar in manner to that described for Fig. 1.

This construction has not only the advantage of permitting a small lower end bushing construction but it permits the bushing 10 to be secured to the cover of the housing or tank for the electrical apparatus before the cover is secured in place. When the submerged leads have been properly placed, the cover of the tank, carrying the bushings secured in place on it, can be brought into position and fastened to the tank. The connections with the submerged leads are then made merely by rotating the capstan nuts. All fishing for leads and electrical connections 20 to be made under the oil or surface of the fluid insulating medium in the tank are thus avoided.

It is obvious that bushings of my invention may be removed from the cover of enclosed electrical apparatus with equal facility since the manipulation of the capstan nuts is all that is required to disconnect the bushings from the electrical apparatus.

While I have here shown two embodiments of my invention which are, at present, the best means known to me for carrying the same into effect, I would have it understood that this is merely illustrative and that I do not mean to be limited thereby to the 35 precise details here disclosed since obvious alterations thereof will occur to those skilled in this art, nor in the choice of recognized equivalents except as defined in my claims hereunto annexed.

What I claim as new and desire to secure by Letters Patent of the United States, is:—

1. In a high voltage bushing structure, the combination with a conductor, of a conducting sleeve, an insulating cylinder surrounding said conductor, insulating material overlying the surface of said cylinder intermediate its ends, said material being snugly fitted between said cylinder and sleeve and having its ends formed into 45 barriers, distance sleeves supporting said barriers in predetermined positions, and an exterior insulating member having an insulating filling enclosing the barrier structure on one side of said conducting sleeve.

2. A high voltage bushing of the type described comprising a tubular conductor, an insulating structure surrounding the same, and a threaded rod in said tubular conductor having an external manipulating device for rotating said rod into and out of threaded engagement with a cooperating lead entering said tubular conductor.

3. A high voltage bushing of the type described comprising a tubular conductor, an 60 insulating structure surrounding the same,

and a threaded conducting rod in said tubular conductor having an externally operable nut rotatable in one end of said tubular conductor, said rod being arranged to be rotated into and out of threaded engagement 70 with a cooperating lead entering the other end of said tubular conductor.

4. A high voltage bushing of the type described comprising a tubular conductor, an insulating structure surrounding the same, and a threaded conducting rod in said tubular conductor having a capstan nut secured thereto and arranged to turn in one end of said tubular conductor, the thread on said rod being arranged to engage with and hold snugly against said tubular conductor a cooperating lead entering the other end of said tubular conductor.

5. The combination with a conducting tube, of an insulating cylinder surrounding said tube having a countersunk formation overreaching one end of said tube, an external insulating structure surrounding the other end of said tube and cylinder, a conductor in said tube, a winding lead encased in insulation provided with a complementary end formation adapted to fit snugly in the overreaching portion of said cylinder, and means operable from the exterior of 80 said tube for uniting said conductor and lead.

6. The combination with a conducting tube, of an insulating cylinder surrounding said tube having a countersunk formation overreaching one end of said tube, a conducting sleeve surrounding said cylinder intermediate its ends, an external insulating member secured between said sleeve and the other end of said tube, a conductor in said tube, a winding lead encased in insulation provided with a complementary end formation adapted to fit snugly into the overreaching portion of said cylinder, and means operable from the exterior of 90 said tube for uniting said conductor and lead.

7. In a bushing structure the combination with a conducting tube having an insulating cylinder surrounding said tube having a countersunk formation overreaching one end of said tube, the other end of said tube protruding, a conducting sleeve surrounding said cylinder intermediate its ends, layers of insulating material snugly fitted between said sleeve and cylinder, a conducting cap secured to the protruding end of said tube, and an external insulating member adapted to contain an insulating filling secured between said cap and sleeve,

of a conducting rod in said tube, a winding lead adapted for threaded engagement with said rod encased in insulation, said encasing insulation provided with a complementary end formation adapted to fit snugly into the overreaching portion of said cylinder, and means on an exterior portion of said rod

operable for drawing said rod and lead together to form an unbroken exterior insulating surface.

8. In a bushing structure the combination with a conducting tube, having an insulating cylinder surrounding said tube and overreaching one end of said tube and provided with a countersunk formation having a flared conical bore tapering off toward the 10 end of said tube, the other end protruding from the cylinder, a conducting sleeve surrounding said cylinder intermediate its ends and formed to provide an electrostatic flux controlling shield, a conducting cap formed 15 to control the flux in conjunction with said
- sleeve secured to the protruding end of said tube, and an external insulating member adapted to contain an insulating filling secured between said cap and sleeve, of a conducting rod in said tube having a threaded 20 inner end and a capstan nut on the outer end, and a winding lead provided with enclosing insulation having a complementary end formation tapered to coincide with the taper in the overreaching portion of said 25 cylinder and adapted for threaded engagement with said rod.

In witness whereof, I have hereunto set my hand this 27th day of Dec. 1918.

ALLAN B. HENDRICKS, JR.
